TOY PISTOL.

Filed Jan. 12, 1929

UNITED STATES PATENT OFFICE

THOMAS O. SCHRADER, OF ALLENTOWN, PENNSYLVANIA, ASSIGNOR TO THE DENT HARDWARE CO., OF FULLERTON, PENNSYLVANIA, A CORPORATION OF PENNSYLVANIA

TOY PISTOL

Application filed January 12, 1929. Serial No. 332,177.

This invention, generally stated, relates to toy pistols and has more especially relation to that type of toy pistol known in the trade as a repeater cap pistol.

5 One object of the present invention is to provide a toy pistol of the character stated in which is provided a star wheel and a hammer simultaneously operable by a trigger operated pawl, the star wheel feeding a strip 10 of cap tape and the hammer cooperating with an anvil block.

A further object of the present invention is to provide a fixed stud upon the pistol casing upon which stud is loosely mounted the 15 star wheel and hammer as operated by the trigger and pawl.

A still further object of the present invention is to provide a structure of the character stated in which the trigger operated pawl 20 is constructed simultaneously to engage and operate a star wheel and hammer, the star wheel being provided with peripheral and laterally extended pins with which the pawl engages and the hammer being provided with 25 a flange for pawl engagement.

A still further object of the present invention is to provide a coiled spring arrangement for returning the trigger operated pawl to normal position and a leaf spring for causing impact of the hammer with the anvil 30 block.

A further object of the present invention is to provide an arrangement, combination, and connection of parts for attaining the 35 results sought by the foregoing objects.

The invention consists of the novel construction hereinafter described and finally claimed.

40 The nature, characteristic features and scope of the invention will be more fully understood from the following description taken in connection with the accompanying drawings forming part hereof, and in which:

45 Fig. 1, is a view in side elevation of a toy pistol embodying the invention.

Fig. 2, is a view in elevation with one of the cover plates removed.

50 Fig. 3, is a view in cross section taken upon the line 3-3 of Fig. 2.

Fig. 4, is a view in perspective of the pistol trigger.

Fig. 5, is a view in perspective of the pawl.

Fig. 6, is a view in perspective of the pistol hammer.

55 Fig. 7, is a view in perspective of the star wheel as operated by the pawl shown in Fig. 5.

Fig. 8, is a view in perspective of the cap tape guide shown in Fig. 2.

60 For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

65 Referring to the drawings in detail, the frame or shell in which the operative parts of the toy pistol are mounted is in two half sections and are designated by the reference numerals 1 and 2. These parts are secured together by means of the screws 3 and 4, see Fig. 1. The handle 5 of the pistol is provided with a magazine chamber 6 to receive the cap 70 tape 7. The cap tape which is in the form of a reel is introduced through an opening in the handle 5 which is closed by cover 8. The cap tape 7 is fed upwardly from the magazine chamber 6 by a star wheel 9 between the anvil 75 block 10 and the hammer 11, best seen in Fig. 2. The cap tape 7 as it is fed upwardly by the star wheel 9 is guided by the flat surface of the member 12, which member is best seen in Fig. 8. This member 12 is provided with a

80 cut-away portion 13 which engages over the rear of the anvil block 10 and is spring 85 pressed as at 14 in order to keep the upper portion of the member 12 in engagement with the anvil block. The star wheel 9 is loosely 90 mounted upon a stud 15 extended laterally from the housing or shell 1, see Fig. 2, and also loosely mounted upon the same stud 15 is the hammer 11. Taking up first the star 95 wheel, which is best seen in Fig. 7, it is to be 100

noted that the one face thereof is provided peripherally with a series of laterally extended pins 16. These pins 16 are adapted to be engaged by the notched portion 17 of the nose 18 of the pawl 19. This pawl is pivoted as at 20 to the upper end 21 of the trigger 22. The trigger 22 is fulcrumed as at 23 to the shell 1 of the opposite casing. The outer end 24 of the pawl 19 is provided with a lug 25 and a coiled spring 26 connects this lug 25 with a pin 27 fixed to the shell or casing 1. Thus, as the trigger 22 is moved around its fulcrum point 23 in the direction of the arrow in Fig. 2, the nose 18 of the pawl 19 moves in a counter-clockwise direction, the star wheel 9 thus moving upwardly the cap tape and at the same time moving toward the left in Fig. 2 the hammer 11; or, in other words, moving the hammer away from the anvil block. The hammer 11 which is loosely mounted upon the stud 15 with the star wheel 9 is moved toward the left in Fig. 2 by reason of the fact that the notched part 28 of the pawl 19 is in engagement with the finger 30 of the hammer. The hammer 11 is notched as at 31 and a leaf spring 32 cooperatively engages with the notched part 31 of the hammer, the function of which leaf spring is that of causing the hammer to explode a charge of powder upon the cap tape at time of impact of the hammer with the anvil block. In other words, the trigger and its pawl are returned to normal position by means of the coiled spring 26 independently of the leaf spring 32 which returns the hammer 11 to functioning position. By this arrangement and construction of parts the cap tape is automatically fed upwardly by trigger movement and the same trigger movement causes the hammer 11 to move to functioning position.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

1. In a device of the character stated, a magazine for cap tape, an anvil block, a stud, a star wheel loosely mounted upon said stud operative to feed said tape to said anvil block, a plurality of peripherally arranged, laterally extended pins upon said star wheel, a trigger, a spring pressed pawl pivoted to said trigger and arranged to engage said pins, and a spring pressed hammer loosely arranged upon said stud and engaged by said pawl and moved outwardly with the pawling of said star wheel.

2. In a device of the character stated, a

magazine for cap tape, an anvil block, a stud, a star wheel loosely mounted upon said stud operative to feed said tape to said anvil block, a plurality of peripherally arranged, laterally extended pins upon said star wheel, a trigger, a spring pressed pawl pivoted to the end of said trigger as arranged above the pivot point of the trigger, said spring pressed pawl being arranged to engage said pins, and a spring pressed hammer loosely arranged upon said stud and engaged by said pawl and moved outwardly with the pawling of said star wheel.

3. In a device of the character stated, a magazine for cap tape, an anvil block, a stud, a star wheel loosely mounted upon said stud operative to feed said tape to said anvil block, a plurality of peripherally arranged, laterally extended pins upon said star wheel, a trigger, a spring pressed pawl pivoted to said trigger and arranged to engage said pins, said spring being coiled and engaging said pawl beyond its pivotal connection with said trigger, and a spring pressed hammer loosely arranged upon said stud and engaged by said pawl and moved outwardly with the pawling of said star wheel.

4. In a device of the character stated, a magazine for cap tape, an anvil block, a stud, a star wheel loosely mounted upon said stud operative to feed said tape to said anvil block, a plurality of peripherally arranged, laterally extended pins upon said star wheel, a trigger, a spring pressed pawl pivoted to said trigger and arranged to engage said pins, and a spring pressed hammer loosely arranged upon said stud and engaged by said pawl and moved outwardly with the pawling of said star wheel, said hammer being notched and engaged by said spring which is relatively flat.

THOMAS O. SCHRADER.
